S. E. GILL

SIGN SUPPORT

Filed April 4, 1923

Patented June 24, 1924.

1,499,169

UNITED STATES PATENT OFFICE.

SAMUEL E. GILL, OF VIRGINIA, ILLINOIS.

SIGN SUPPORT.

Application filed April 4, 1923. Serial No. 629,842.

To all whom it may concern:

Be it known that I, SAMUEL E. GILL, a citizen of the United States, residing at Virginia, in the county of Cass and State of Illinois, have invented certain new and useful Improvements in Sign Supports, of which the following is a specification.

This invention relates to supports, and more particularly to sign supports.

10 An object of the invention is the provision of a support for securing a sign to a post at right angles to a roadway, whereby advertising matter may be more readily seen.

15 A further object is the provision of a support consisting of a pin adapted to be received in an eye formed on the end of an arm secured to the sign, and suitable bracing means comprising a pair of arms secured to the outer end of the sign and diverging, the 20 inner ends of the arms being secured to a transverse member carried by said pin.

In the accompanying drawings, I have shown one embodiment of the invention. In this showing:

25 Figure 1 is a perspective view showing the sign and support attached to a post,

Figure 2 is a front elevation of the sign in position,

Figure 3 is a horizontal sectional view,

30 Figure 4 is a detail view of the pin and arm, and,

Figure 5 is a detail sectional view on line 5—5 of Figure 2.

Referring to the drawings, the reference 35 numeral 1 designates a roadway and 2 a pole arranged beside the roadway. The sign consists of a skeleton frame formed of two sections 3. A sign board 4 is secured between these sections. By providing a sign constructed in this manner, the sign board may 40 be removed and replaced by another, containing different advertising matter and the sign boards may be interchangeable.

The support consists of means for supporting the weight of the sign and means 45 for bracing the sign against strains caused by the wind and other causes.

An arm 6 is secured to the sign adjacent 50 the top and bottom and projects slightly therefrom. The outer end of each of these arms is provided with a sleeve 7. A pin 8 is placed through the pole or other support and this pin is provided with an offset end 9 which is vertically arranged. This offset 55 end is adapted to be received in the sleeve 7. It will be apparent that the arrangement

of the ends of the pins in the sleeves will support the weight of the sign, and will also permit the sign to swing upon the pin as a pivot when any force, such as the force 60 of the wind is applied to either face of it. Suitable means are provided to retain the sign in the desired position. As shown, a collar 10 is arranged on the pin at a distance from its end. A transverse member 11 is 65 adapted to be arranged between this collar and the pole. A brace 12 is secured to the outer edge of each side of the sign. As shown, these braces are retained in position by bolts 13 passing through the frame of the 70 sign and through suitable openings in the arms. The inner ends of these arms are offset, as at 14, and arranged adjacent the transverse arm 11. A curved arm 15 extends around the other side of the pole and is provided with offset ends 16, arranged in the 75 opposite sides of the transverse member 11. The offset ends of these arms are secured to the transverse member 11 by bolts 17. The curved arm 15 is provided with a centrally 80 arranged opening adapted to receive the end of the pin 8, which projects through the pole. As shown, this end of the pin is threaded, as at 18, and is adapted to receive a nut 19.

85 The construction of the sign will be obvious from the foregoing description. It is assembled by arranging the pins in the pole at the proper distance from each other with the transverse members 11 arranged thereon. 90 The washers 10 retain the transverse members in their proper position. The sign is assembled and the sleeves 7 slipped over the vertical portions 9 of the pins. The arms 12 and 15 are then secured in position and 95 the bolts 17 passed through the offset ends of these arms and the transverse member 11. The nut 19 is then placed on the threaded end of the pin 8. When assembled, the sign is properly supported on the pole to 100 permit advertising matter thereon to be readily seen and the bracing arms 12 support the sign against any forces that would tend to move it from its desired position.

105 It is to be understood that the form of the invention herewith shown and described is to be taken as a preferred example of the same, and that various changes in the shape, size, and arrangement of parts may be resorted to without departing from the spirit 110 of the invention or the scope of the subjoined claims.

Having thus described my invention, I claim:

1. In a device of the character described, a plurality of arms adapted to be secured to one edge of a sign, said arms being provided with sleeves on their outer ends, pins mounted in a suitable support and provided with offset ends adapted to be received in said sleeves, braces secured to the other edge of said sign and extending toward said support, said braces diverging from each other toward their opposite ends, and means for connecting the ends of said braces to each other and to the support.
- 15 2. In a device of the character described, a plurality of arms adapted to be secured to one edge of a sign, said arms being provided with sleeves on their outer ends, pins mounted in a suitable support and provided with offset ends adapted to be received in said sleeves, braces secured to the other edge of said sign and extending toward said support, said braces diverging from each other toward their opposite ends, trans-
- 20 20 with offset ends adapted to be received in said sleeves, braces secured to the other edge of said sign and extending toward said support, said braces diverging from each other

toward their opposite ends, and a transverse member carried by each of said pins and connected to the ends of said braces.

3. In a device of the character described, a plurality of arms adapted to be secured to one edge of a sign, said arms being provided with sleeves on their outer ends, pins mounted in a suitable support and provided with offset ends adapted to be received in said sleeves, braces secured to the other edge of said sign and extending toward said support, said braces diverging from each other toward their opposite ends, transverse arms carried by said pin, and connected to the ends of said braces, and curved arms connected to said transverse arms and extending on the opposite side of said support.

In testimony whereof, I affix my signature in presence of two witnesses.

SAMUEL E. GILL.
